MACHINE FOR DISPENSING LIQUIDS

Leo M. Harvey, Los Angeles, Calif.

Application June 26, 1950, Serial No. 170,354

5 Claims. (Cl. 103—148)

1

This invention relates to a machine for dispensing liquids and it is a general object of the invention to provide a machine or mechanism useful generally for handling liquids and which is particularly applicable to vending machines where liquid is to be handled or dispensed in measured quantities.

A general object of the invention is to provide a machine of the general character referred to which is of simple and inexpensive construction, which is positive and accurate in operation and which is simple and convenient to service.

A general object of this invention is to provide a liquid handling or dispensing mechanism that can be employed to advantage in liquid vending machines, the mechanism being characterized by pincher type chokes controlling the inlet and outlet of liquid relative to a measuring cell and a pincher type press collapsing the cell to discharge liquid therefrom.

Another object of this invention is to provide a machine of the general character referred to characterized by pivotally mounted cam operated carriers operating parts that cooperate to act on the liquid carrying unit.

It is a further object of the invention to provide a mechanism of the general character referred to in which an operating means is provided for the elements acting on the liquid carrying unit, which operating means involves a single cam shaft operating a plurality of control cams so that the mechanism operates in a predetermined manner when the shaft is rotated.

It is a further object of the invention to provide a mechanism of the general character referred to involving few, simple, easily formed parts that are convenient to mount ready for operation, and which are such as to operate accurately and dependably over a long period of time without requiring servicing or repair.

In the machine provided by the invention there is a frame that carries the working parts and a container is supported by the frame and carries a supply of liquid. A liquid handling unit receives liquid from the container and in its preferred form involves an inlet duct, a collapsible cell supplied by the inlet duct, and an outlet duct receiving liquid from the cell. The said unit is preferably formed of rubber, or like material, and is such that it can be manufactured cheaply to be expendable when the container is emptied. The unit handling the liquid is operated by a closure means or inlet choke, a closure means or outlet choke, and a collapsing means acting on the cell.

2

The inlet choke preferably involves relatively movable shoes at opposite sides of the inlet duct and carriers that support the shoes for the desired relative movement, that is, for movement between a position where the inlet duct is open or unobstructed and an actuated position where the inlet duct is collapsed or choked so that liquid cannot flow therethrough. In the preferred form of the invention the carriers are pivotally mounted and they may be carried on separate mounting posts.

The outlet choke preferably corresponds in construction with the inlet choke except that it cooperatively engages the outlet duct. The collapsing means for the cell may correspond in construction with the chokes except that it has pressure plates that engage the cell instead of the shoes that engage the ducts. In a preferred embodiment of the invention the carriers of the chokes and of the collapsing means are carried on two posts which are parallel and spaced apart.

An operating means actuates the carriers of the chokes and the carriers of the collapsing means. In the preferred form of the invention the carriers of the inlet choke have arms with a tension spring connected between them normally yieldingly holding the carriers so that the shoes thereof are apart. In like manner arms and tension springs are provided on the carriers of the outlet choke and of the collapsing means.

The operating means further includes cam means operating the carriers above referred to and it preferably involves a single rotating cam shaft with an inlet cam thereon operating the inlet choke, an outlet cam operating an outlet choke and a pressure cam operating the collapsing means. The cams are operatively connected with the carriers to be actuated thereby and it is preferred that the operating connections be through cam followers and yielding means such as compression springs, which provide for overtravel of the followers. The cam shaft is driven by power means, for instance, by means of a motor through a speed reducing mechanism.

The various objects and features of my invention will be fully understood from the following detailed description of a typical preferred form and application of the invention, throughout which description reference is made to the accompanying drawings, in which:

Fig. 1 is a vertical view of a mechanism embodying the present invention with certain parts broken away to show in section. Fig. 2 is a vertical sectional view of parts shown in Fig. 1, being a view taken as indicated by line 2—2 on Fig. 1.

and showing the parts related as they are when the machine is in the normal unactuated condition. Fig. 3 is a view similar to Fig. 2 showing the machine partially operated so that both chokes are engaged, closing both ducts. Fig. 4 is a view similar to Figs. 2 and 3, showing the machine further operated, in which case the inlet duct remains closed while the outlet duct is open and the cell is being collapsed. Fig. 5 is an enlarged plan section of the inlet choke, being a view taken as indicated by line 5-5 on Fig. 1. Fig. 6 is an enlarged plan section showing the collapsing means, being a view taken as indicated by line 6-6 on Fig. 1, and Fig. 7 is an enlarged plan section of the outlet choke, being a view taken as indicated by line 7-7 on Fig. 1.

The mechanism provided by this invention is useful, generally, where liquid is to be dispensed, and is particularly useful where liquid is to be dispensed in measured quantities, as, for example, in a liquid vending machine, or the like. The particular form of the invention shown in the drawings is intended for use in a vending machine, or in a like situation, and it may be adapted to handle liquid from containers of different types, as for instance, containers such as are the subject of my copending applications entitled "Mechanism for Dispensing Liquid" and "Liquid Dispensing Machine," Serial No. 170,352, now Patent No. 2,647,661 and 170,353, respectively, filed on even date herewith. Further, the present invention may be adapted to or incorporated in multiple machines where liquid is handled from a plurality of containers and in such case suitable controls may be provided, such as are set forth in my copending application entitled "Mechanism for Dispensing Liquid" above identified.

The machine as shown in the drawings involves, generally, a frame A, a liquid carrying container B, a liquid handling unit C with an inlet duct 10, a collapsible cell 11 and an outlet duct 12, a closure means or inlet choke D, a closure means or outlet choke E, cell collapsing means F, operating means G for the chokes, and collapsing means and drive means H for the operating means G.

The frame A may, in practice, vary widely in form and construction, and serves primarily as a mounting or carrier for the other parts of the machine. Further, the container B may vary widely in form and construction, as I have indicated above. In the case illustrated it is a simple liquid carrying container with a liquid outlet or delivery fitting at its bottom.

The liquid handling unit C is arranged to receive liquid from the fitting 15 and may be applied directly thereto, as shown in the drawings. In its preferred form the unit C is a single body or structure formed of rubber, or rubber-like material, and the inlet duct of the unit is a simple, elongate tube open at its upper end for application to or connection with the fitting 15. The collapsible cell 11 is an elongate tubular part in communication with the lower end of the inlet tube 10 and is preferably of a predetermined capacity. The outlet duct 12 is an elongate tubular part with its upper end in communication with the cell 11. The lower end portion 12a of the duct 12 preferably closes the duct and is subject to being severed from the balance of the duct, as along a line 16, when the structure is made ready for operation.

In a typical application of the invention the unit C, above described, may be a thin-walled

5 rubber or rubber-like element of inexpensive manufacture and may be sealed with or applied to the container B to be installed in the machine with the container, which may be a paper carton or other cheap unit, expendable when empty.

10 The closure means or inlet choke D, best shown in Fig. 5 of the drawings, is characterized by two relatively movable shoes 20 located at opposite sides of the inlet duct 10 of unit C. Carriers 21 support the shoes 20 and are movable or shiftable to operate the shoes between positions where they are apart, as shown in Fig. 5, leaving the inlet duct open and free to pass liquid, and an operated position where the shoes are in, or in pressure engagement with the duct 10, collapsing it as shown in Figs. 3 and 4, in which case the duct 10 is closed against the passage of fluid.

15 In the preferred form of the invention the carriers 21 are pivotally supported on one or more pivotal mountings or posts. In the case illustrated each carrier 21 is supported on a post 22 and the posts are parallel and spaced apart so that the carriers 21 are clear of each other. By spacing the pivotal mountings of the carriers the 20 shoes 20 remain in substantial parallelism throughout operation so that there is little or no tendency for the inlet duct to be squeezed from the shoes as the mechanism operates.

25 The closure means or outlet choke, best shown in Fig. 7 of the drawings, may be the same in construction as the means C just described. As shown in the drawings, the choke means E includes shoes 25 at opposite sides of the outlet duct 12 and the shoes 25 are supported by carriers 26 pivotally mounted on posts 22 in the manner described with reference to the carriers 21. In Fig. 7 of the drawings the carriers are shown operated so that the shoes 25 are in pressure engagement with the outlet duct 12 closing it against the passage of fluid.

30 The collapsing means F, best shown in Fig. 6 of the drawings, may be of the type of construction employed in the means C and E. As shown in the drawings the means F may include pressure shoes or plates 28 at opposite sides of the collapsible cell 11 and the shoes 28 may be supported by carriers 29 supported by posts 22.

35 It is notable that in accordance with the preferred form of the invention the carriers 21, 26 and 29 are supported by common posts 22 so that only two posts are required in the machine. When such construction is employed spacers 30 may be provided between the carriers on the posts so that the carriers are located in the desired spaced relation lengthwise of the posts. It will be apparent how the posts can be readily mounted in or supported from this frame.

40 The operating means for the carriers 21 of the inlet choke is shown as including a spring 40 normally yieldingly urging the carriers 21 apart so that they are spaced in a manner such as is shown in Fig. 5 of the drawings. In the case illustrated the carriers have arms 41 projecting therefrom so they are spaced apart and the spring 40 is a tension spring connected between the arms, as clearly shown in Fig. 5. The operating means further includes a cam mechanism for operating the carriers to a position where they squeeze or collapse the inlet duct 10 and thus stop flow therethrough.

45 In the preferred form of the invention the cam means involves a cam 45 on a rotating cam shaft 46 and suitable operating or driving connections between the cam 45 and the carriers 21. In the case illustrated the desired connections between

the cam and carriers are provided through cam followers 46 that are operated by the cam and springs 47 which communicate motion from the followers to the carriers and provide for overtravel of the followers after the carriers have been moved to position where the shoes 20 are in full clamping engagement with the inlet duct 10. In the preferred arrangement there is a cam follower 46a for each carrier 21 and the cam followers are pivoted on the posts 22 adjacent the carriers 21 and engage the periphery of the cam 45. The springs 47 are compression springs and act between the followers 46 and shoulders 48 on the arms 41 projecting from the carriers 21. Suitable adjusting screws 49 act between the shoulders 48 and the springs 47 so that the action of the structure can be varied as desired.

From Fig. 5 it will be noted that the cam 45 is of balanced formation and such that when the cam is in the position shown in Fig. 5 the followers are in allowing the spring 40 to hold the arms 41 in, in which case the carriers 21 hold the shoes 20 apart. As the cam is rotated from the position shown in Fig. 5 the followers 46a are moved out or spread apart thus causing the arms 41 to be spread apart and the shoes 20 to be moved in or toward each other.

The operating means G for the outlet choke E may be the same as that just described and, as shown in the drawings, corresponding parts of means D and E are correspondingly numbered. It is to be observed, however, that the cam operating the means E is of a shape different from that operating the means C with the result that the means C and E are operated oppositely.

The means G operating the collapsing means F may correspond in construction with the operating means related to means C and means E, as shown in Fig. 6 of the drawings, and therefore, corresponding parts are numbered the same as in the case of means C and 3. It is to be noted, however, that the cam operating the collapsing means F is shaped differently from the other cams so that the shoes or pressure plates 28 of means F operate in the desired manner and in the proper timed relation to the means C and E.

With the operating means G provided as above described, I prefer to employ a common cam shaft 46 to carry the several cams and the cam shaft is supported in the frame A so that it rotates and thus turns the cams in the desired manner.

The drive means H for the operating means G may be any suitable structure serving to rotate the cam shaft 46, it being preferred, in practice, that the cam shaft be intermittently rotated under the influence of a suitable control governing the action of means H. The means H shown in the drawings involves a prime mover or motor M operating through a speed reducing mechanism 60 that drives the cam shaft 46.

From the drawings, and particularly from a consideration of Figs. 5, 6 and 7 of the drawings, it will be understood how the mechanism, when in the normal position, as illustrated in Figs. 5, 6 and 7, has the outlet duct closed against the passage of fluid, while the inlet duct is open and the collapsible cell expanded, so that liquid from the container B is free to fill into the cell. When the cam shaft is rotated, as by energization of the motor, the means F remains engaged so that the outlet duct remains closed until such time as the means C has been operated to close the inlet duct 10. Immediately following closing of the

inlet duct the means E operates to open the outlet duct 12 and the collapsing means F starts to collapse the cell 11 with the result that liquid is forced from the cell and out through the duct 12. As the cell is collapsed and throughout the discharge of liquid from the cell and outlet duct, the inlet duct remains closed off. When the cell has been emptied the means F returns to the position shown in Fig. 1 and as it approaches the unactuated position the outlet duct is closed by means E, and the inlet duct is released or opened by means C so that when the mechanism reaches the unactuated position the parts are re-established in the relationship shown in Figs. 5, 6 and 7.

By providing the overtravel springs 47 in the mechanisms hereinabove described the clamping action that occurs on the parts or elements of the liquid handling unit can be varied and the mechanism can be designed for inexpensive manufacture, in that great accuracy is not required. Any inaccuracy occurring in the cams or relationship of parts can be compensated for so long as there is sufficient movement or travel imparted to the cam followers to gain full operation of the parts that engage the liquid handling unit. It is to be observed that the mechanism as provided by the present invention is such that the liquid handling unit can be readily arranged in or removed from the machine. This is an important consideration when the unit is made cheaply and is to be disposed of when the container on which it is carried has been emptied and is discarded. It is also to be observed that with the mechanism provided by the present invention the liquid handling unit is not deflected from a given position, but rather, remains vertical or on the same vertical axis at all times.

Having described only a typical preferred form and application of my invention, I do not wish to be limited or restricted to the specific details herein set forth, but wish to reserve to myself any variations or modifications that may appear to those skilled in the art and fall within the scope of the following claims.

Having described my invention, I claim:

1. A mechanism of the character described including, a liquid handling element having an upper inlet duct, a central collapsible cell receiving liquid from said duct and a lower outlet duct delivering liquid from the cell, control means at the inlet duct and acting on the inlet duct to stop flow therethrough, operating means at the cell and acting on the cell to collapse it, control means at the outlet duct and acting on the outlet duct to stop flow therethrough, and a cam mechanism operating the control means and operating means in synchronism, each of said means including, oppositely relatively movable operating members with substantially parallel clamp faces engaging said element when said members are in a fully operated position, cam operated arms, yielding force transmitting elements between the arms and said members, and spaced parallel rods each pivotally supporting an operating member and an arm.

2. A mechanism of the character described including, a liquid handling element having an upper inlet duct, a central collapsible cell receiving liquid from said duct and a lower outlet duct delivering liquid from the cell, control means at the inlet duct and acting on the inlet duct to stop flow therethrough, operating means at the cell and acting on the cell to collapse it, control means at the outlet duct and acting on the outlet duct

to stop flow therethrough, and a cam mechanism operating the control means and operating means in synchronism, each of said means including, spaced parallel rods, opposed oppositely relatively movable operating members pivotally carried by the rods and engaging said element, a spring between said members normally yielding urging the members apart, cam operated arms pivotally carried by the rods, and yielding elements operated by the arms and engaged with the members to operate said members toward each other.

3. A mechanism of the character described including, a liquid handling element having an upper inlet duct, a central collapsible cell receiving liquid from said duct and a lower outlet duct delivering liquid from the cell, control means at the inlet duct and acting on the inlet duct to stop flow therethrough, operating means at the cell and acting on the cell to collapse it, control means at the outlet duct and acting on the outlet duct to stop flow therethrough, and a cam mechanism operating the control means and operating means in synchronism, each of said means including, spaced parallel rods, opposed relatively movable pivotally mounted operating members carried by the rods and engaging said element, a spring between said members normally yielding urging them apart, pivotally mounted cam operated arms carried by the rods, said means having element engaging faces, and springs between the arms and said members whereby the faces of said members are yielding urged toward each other when the arms are operated.

4. A mechanism of the character described including, a liquid handling element having an inlet duct, an elongate collapsible cell and an outlet duct, the inlet and outlet ducts being substantially smaller in diameter than the cell and being in communication with the cell at the ends thereof, control means at the inlet and outlet ducts controlling flow through the ducts and including relatively movable opposed members engaging

opposite sides of the ducts, and operating means at the cell operating on the cell to collapse it and including relatively movable opposed members engaging opposite sides of the cell, positive drive means having a cam shaft operating the control means and operating means, and yielding elements between the cam shaft and said opposed members whereby said members are yieldingly operated in opposite directions to successively close and open the ducts and squeeze and release the cell.

5. A mechanism of the character described including, a liquid handling element having an upper inlet duct, a central collapsible cell receiving liquid from said duct and a lower outlet duct delivering liquid from the cell, control means at the inlet and outlet ducts controlling flow through the ducts, and operating means at the cell operating on the cell to collapse it, the said operating means including relatively movable members having clamp faces engaging opposite sides of the cell and pivotally mounted actuators mounted on spaced parallel axes and cooperatively related to the members and operating between the members to actuate them in opposite directions to successively squeeze and release the cell, said clamp faces being opposed and substantially parallel with each other when fully operated by the actuators to the position where the cell part between them is collapsed against passage of liquid through it.
